CLAIM

We claim the ornamental design for a disk drive carrier for a network attached storage unit, as shown and described.

DESCRIPTION

FIG. 1 is a front, right perspective view of the disk drive carrier for a network attached storage unit;

FIG. 2 is a front, left perspective view of the disk drive carrier;

FIG. 3 is a front view of the disk drive carrier;

FIG. 4 is a greatly enlarged top view of the disk drive carrier;

FIG. 5 is an enlarged left side view of the disk drive carrier;

FIG. 6 is an enlarged right side view of the disk drive carrier;

FIG. 7 is an enlarged rear view of the disk drive carrier; and,

FIG. 8 is a greatly enlarged bottom view of the disk drive carrier.
